UNITED STATES PATENT OFFICE.

ARTHUR MOGG BROWN, OF LINCOLN, ENGLAND.

PORTABLE TABLE, BOOK-REST, &c.

SPECIFICATION forming part of Letters Patent No. 729,919, dated June 2, 1903.

Application filed March 9, 1903. Serial No. 146,888. (No model.)

To all whom it may concern:

Be it known that I, ARTHUR MOGG BROWN, a subject of the King of Great Britain and Ireland, residing at Lansdowne, The Avenue, Lincoln, England, have invented certain new and useful Improvements in Portable Tables, Book-Rests, and the Like, of which the following is a specification.

This invention relates to portable tables, book-rests, or the like intended to be supported on the knee of the user when traveling or reclining in a chair or couch. Rests of this kind, comprising a pad or table-top hinged to a Δ -shaped bracket, are already known, the Δ -bracket when in use resting on the knee of the user. The tops, however, are so hinged to the bracket that while they are capable of being folded flat in one direction they do not admit of the top being adjusted or rocked to either side of the bracket.

The object of the present invention is to provide a rest of the above-described nature, but in which the top is capable of being rocked or adjusted and, if desired, folded flat to either side of the bracket indiscriminately, thus affording much more convenience to the user, especially in a traveling vehicle, the oscillations of which are otherwise difficult to contend with, but which with a table according to the invention are practically neutralized.

In the accompanying drawings, Figures 1 and 2 are respectively elevation and plan of one form of the improved table; Figs. 3 and 4, elevations illustrating the adaptability of the table; Fig. 5, an elevation illustrating the manner in which the table may be collapsed or folded flat. Figs. 6, 7, and 8 are detail elevations illustrating a modified form.

In carrying out the invention in one convenient manner a table-top rest or pad *a* is provided with a supporting-bracket comprising two flaps, wires, or frames *b b*, hinged to a distance-piece *c*, secured to the top. The flaps, made of any suitable material, are connected by limiting-straps *e*. The hinges *d* are of a nature admitting movement of the flaps *b* in either direction in order that the top may be adjusted or inclined to either side indiscriminately, as shown by Figs. 3 and 4, where *f* represents the knee of the user and

g a flat surface, such as an ordinary table. It will thus be obvious that as the top can be adjusted or inclined to either side the user can easily attain the most convenient position or inclination to suit the particular circumstances under which he may desire to use the table, whether as a writing-desk or as a book-support. The free adjustment afforded also enables the user to contend with the oscillations of the vehicle in which he may be traveling. When out of use, the nature of the hinges also admits of the flaps *b* being folded to either side indiscriminately, as shown by full and dotted lines in Fig. 5.

Instead of employing ordinary hinges *d* and a distance-piece *c*, double hinges *h* may be used, as shown in Figs. 6 to 8. In this case also the table may be inclined to either side or the flaps *b* folded to either side, as desired.

When the improved table is intended for writing purposes, the top may be fitted with corner-clips *k* for paper, or other useful fittings may be similarly provided.

Having thus described my invention, what I claim as new, and desire to secure by Letters Patent, is—

1. A portable table, desk or rest, comprising a top, a distance-piece on the under surface thereof, supporting-flaps hinged to said distance-piece and adapted to oscillate about their hinges in either direction relatively to the top, and limiting-straps connecting said flaps.

2. A portable table, desk or rest, comprising a top; supporting-flaps connected to the under surface of said top by double hinges for the purpose of allowing the flaps to oscillate in either direction relatively to the top, and limiting-straps connecting said flaps.

3. A portable table, desk or rest, comprising a top, fittings thereon for paper, supporting-flaps hinged to the under surface of the top by double hinges and limiting-straps connecting the flaps.

In witness whereof I have hereunto set my hand in presence of two witnesses.

ARTHUR MOGG BROWN.
